COMESTIBLE CONTAINER

Eveline H. Waldie, Leonia, N. J.

Application June 30, 1937, Serial No. 151,091

6 Claims. (Cl. 206—47)

This invention relates to comestible containers and more especially to such containers adapted to receive and hold comestibles during transportation and for use in dispensing the comestible contents to the individual users.

The invention is especially adapted for comestibles such as candy or other confections or comestibles which may be served to the user by being dispensed directly from the package or container in which they are purchased. I have noticed that in connection with the packaging of certain comestibles, such for example as candy, when served directly from the package or box in which it is purchased, the fingers of the users become soiled or sticky from contact with the comestibles and it is customary to use the handkerchief or a napkin to remove such substances from the fingers. I have also noticed that in packages of this character it is customary to employ a soft pad such as cotton batting or the like which is inserted between the inner face of the cover and the contents of the container, serving as a packing pad or buffer to prevent damage of the contents and to securely pack the same in position within the container. I have conceived the idea of a container for comestibles of this nature combining a single unitary structure serving the dual function of a packing pad and also providing a plurality of paper napkins comprising such pad. By this means the same structure which is utilized in place of the usual packing pad will adequately serve not only this purpose but will provide a supply of napkins which may be individually removed for use by those to whom the candy or the like comestible is served.

Further and more specific objects, features and advantages will more clearly appear from the detailed description given below taken in connection with the accompanying drawing which forms a part of the specification.

Referring to the drawing:

Fig. 1 is a longitudinal cross section in elevation illustrating the receptacle with the comestible contents in the container, and with the container closure in position on the container body;

Fig. 2 is a fragmental sectional view showing a part of the container body and certain related parts;

Fig. 3 is an end view illustrating the relationship of certain structural details;

Fig. 4 is a plan view of the device illustrated in the preceding figures with the cover removed; and

Fig. 5 is a fragmental section of the unit illus-

trating a modification of certain structural details.

Referring to the drawing and more particularly to Fig. 1: the container or receptacle body is designated as 1 and is provided with a cooperating closure 2 which is in cooperative position with respect to the side walls of the container body 1. In the embodiment illustrated, the receptacle contains pieces of candy such as 3 which are preferably packed in respectively individual paper shells 4; in the present embodiment the candy being arranged in two layers separated by a cardboard strip 5. A plurality of sheets of relatively soft absorbent material are arranged in superimposed stacked formation to form a pad 6, and the sheets are suitably secured along one edge of said stack as by means of a pair of spaced-apart metallic clamps 7 and 8 provided with stamped-out portions such as 9 which pass through the stack to firmly hold the same in position. A corresponding pair of cooperating clamps 10 and 11 are similarly attached in corresponding spaced relation along the upper marginal edge of a side wall of said container body 1. The clamps 7 and 8 are spaced a slight distance 10 outwardly from the marginal edge of the pad 6 and the clamps 10 and 11 are spaced upwardly a slight distance from the upper marginal edge of the side wall to which they are attached, and a pair of links 12 and 13 pass through the spaces 15 thus provided and serve to securely attach the pairs of clamps 7—8 and 10—11 together. This construction provides a means for hingedly connecting the pad 6 to a side wall of the container body 1 serving to position the pad (Fig. 1) between the inside of the cover 2 and intermediate the cover and the pieces of candy such as 3. The pad thus formed provides the necessary resiliency and thickness desired for a packing pad for packages of this kind; and the attachment means employed is of such a nature as not to interfere with the insertion or removal of the cover 2 as will be clearly indicated in Figs. 1 and 3.

When the cover 2 is removed (Fig. 4), the pad 6 may be removed from the container body 1 and swung outwardly and downwardly to the position indicated in Fig. 2, thereby permitting free access to the candies and the removal of the same from the container. As a candy is removed, an individual napkin may be readily removed from the pad 6; and in this connection it is pointed out that where desired the napkin sheets may be perforated as indicated at 14, so that each sheet may be separated into two individual napkins. When it is desired to replace the cover 2, the pad 6 may

be returned to its normal position as indicated in Figs. 1 and 4, and in such position will serve as a temporary closure in the event that it is desired not to replace the cover member 2.

5 In Fig. 5 I have shown a modification, in which the pad of napkins 6 is attached to an upper marginal edge of the container body 1 by two cooperating strips of tape 15 and 16; the inner faces of the said tapes being adhesively secured 10 at one edge to the respectively opposite sides of the pad 6 and at the other edge to the respectively opposite edges of the upper marginal side wall of the container 1 in the manner clearly indicated. In this embodiment the marginal edges 15 of the sheets comprising the pad 6 are preferably secured together by stitching 17 which also provides for ready severance of the individual sheets from the pad.

Having thus described my invention with particularity with reference to its preferred form, it will be obvious to those skilled in the art, after understanding my invention, that other changes and modifications may be made therein without departing from the spirit and scope of my invention, and I aim in the appended claims to cover such changes and modifications as are within the scope of the invention.

What I claim is:

1. In a combined shipping and serving container for a plurality of pieces of comestibles, the combination of a container body, a closure for said body, a resilient pad adapted to overlie the contents of said body and positioned beneath said closure, said pad comprising a plurality of 30 napkins individually removable for use, and means for pivotally supporting said pad along one edge adjacent the upper edge of a side wall of said body.

2. In a combined shipping and serving container for a plurality of pieces of comestibles, the combination of a container body, a closure adapted for telescoping engagement with said body, a resilient pad adapted to fit within the side walls of said body and to overlie the contents of said body and positioned beneath said closure, said pad comprising a plurality of napkins individually removable for use, and means for pivotally supporting said pad along one edge adjacent the upper edge of a side wall of said body.

3. In a device of the character described, the combination of a container body, a plurality of paper napkins in superimposed stacked relation, spaced-apart clamping means serving to hold said napkins in pad formation, cooperating spaced-apart clamping means secured to the upper edge of one side of said body, and means for hingedly connecting said two pad clamping

means to said second clamping means, whereby said pad may be readily selectively positioned within or without said body.

4. In a device of the character described, the combination of a container body, closure means adapted for interfitting cooperative engagement with said body, a plurality of paper napkins in superimposed stacked relation, spaced-apart clamping means serving to hold said napkins adjacent one marginal edge thereof in pad formation, cooperating spaced-apart clamping means secured to the upper edge of one side of said body, and means for hingedly connecting said two pad clamping means to said second clamping means, said clamping and connecting means permitting said closure means to pass readily thereover to close said container and serving to position said pad closely adjacent the under side of said cover intermediate the same and the container contents.

5. A receptacle for holding comestibles to be dispensed therefrom comprising a container body, a pad comprising a plurality of paper napkin sheets secured together along one edge and permitting removal therefrom of individual 20 of said napkins, and means for hingedly securing said pad adjacent an upper side wall edge of said body, said last means permitting said pad to be selectively positioned within the said body over the contents to serve as a packing pad and to 30 be removed therefrom and folded outside to permit ready access to said contents for removal.

6. In a receptacle for containing pieces of comestible to be eaten from the fingers and which are to be dispensed directly from said receptacle, the combination of a body for holding said comestible, a plurality of paper napkins secured together along one edge to thereby constitute a pad, means for hingedly attaching said napkins adjacent said secured edge to an upper portion 40 of said body, a closure adapted for interfitting engagement with said body and serving to enclose said pad, said attachment means permitting said pad of napkins to lie between the inner face of said closure and over the contents of said body to protect said comestible pieces during transportation and permitting said pad of napkins to be removed from said body and folded outwardly to provide ready access to the contents of said body for removal of the comestibles 45 therefrom, and said napkin securing means permitting ready separation of individual napkins from said pad, whereby said pad serves the dual function of a packing pad and as a source of napkins for use by those to whom the contents 50 are dispensed.

EVELINE H. WALDIE.
